UNITED STATES PATENT OFFICE.

JOSEPH A. WILLIAMS, OF CLEVELAND, OHIO.

TELEPHONE RECEIVER.

Application filed April 21, 1922. Serial No. 555,821.

To all whom it may concern:

Be it known that I, JOSEPH A. WILLIAMS, a citizen of the United States, residing at Cleveland, in the county of Cuyahoga and State of Ohio, have invented a certain new and useful Improvement in Telephone Receivers, of which the following is a full, clear, and exact description.

This invention relates to a telephone receiver adapted for both wireless and ordinary wire telephone systems and is an improvement over the construction constituting the subject matter of my prior application Serial No. 549,832, filed April 5, 1922.

In my prior application referred to, I have disclosed a receiver wherein increased sensitiveness is obtained both by the provision of means whereby the permanent magnet flux is increased, and also by an arrangement wherein there is a larger available space for the coil, permitting a larger number of turns and greater ampere turns for a given current value, with the result that for even a very feeble current a relatively large ampere turn value is obtained.

In said application the above objects were attained by utilizing a cup-shaped metal housing for the coil and its core, and by making use of the housing, core and diaphragm or part of said elements as permanent magnets, the fields produced by the magnets assisting one another to produce an intense flux. By the use of these elements or part of them to produce a permanent magnet flux and by doing away with the permanent magnet which serves that function only, a feature of compactness is obtained to a high degree, and though the size of the receiver as a whole is small, there is a relatively large space permitted for a coil of many turns. Thus with a receiver of a small size, I am able to improve all factors which bring about sensitiveness to minute electric currents in the receiver coil.

The principal object of the present invention is to obtain still greater sensitiveness for the amount of material employed in the receiver; also to provide certain features of construction wherein the housing and core, and if desired, also the diaphragm may be used to greater advantage as permanent magnets. A further object is to so form the diaphragm that when vibrated it is capable of being flexed in a more uniform manner than with an ordinary dia-

phragm, and so that it will give vibrations of greater amplitude for a given change in the flux and thus produce stronger sound waves for given ampere turns in the coil.

In the accompanying sheet of drawings 60 wherein I have shown an embodiment of the invention which operates very effectively, Fig. 1 is a vertical sectional view of a receiver embodying my invention; Fig. 2 is a transverse sectional view of the same; 65 Fig. 3 is a vertical sectional view of the cup-shaped housing detached; Fig. 4 is a similar view of the cup of which the housing is formed, showing how the metal may be removed to form the final desired shape; 70 Figs. 5 and 6 are transverse sectional views on an enlarged scale through a diaphragm formed in accordance with my invention, Fig. 6 showing a slight modification over the construction shown in Fig. 4; and Fig. 75 7 is a face view of the diaphragm.

Referring to the drawings, it will be observed that the receiver here illustrated is of the same general design as that constituting the subject matter of my prior application. The construction herein illustrated includes a cup-shaped housing 10 which receives a coil 11 surrounding a centrally arranged core 12 having at its upper end a slightly enlarged head 12^a and having a reduced lower end 12^b extending through an opening 10^a at the center of the base of the housing 10 and secured in position by nuts 13, the nuts and core serving also to clamp the coil to the base of the cup or housing, the 80 ends of the coil having the usual insulating disks 14.

The upper or open end of the cup-shaped housing 10 is closed by a vibratory diaphragm 15 which is clamped to the top of the housing 10 by a cap 16, preferably formed of insulating material such as rubber, bakelite or the like, this cap having in this instance a down-turned flange 85 threaded on the interior and screwed down onto an externally threaded ring 17, preferably formed separate from the housing for a purpose to be explained, and secured thereto in a suitable manner as by brazing.

In this instance the housing 10 and core 100 12 are preferably formed of good magnet steel and constitute the permanent magnets of the receiver, though as in the preceding case the vibratory diaphragm may also be used as a permanent magnet.

In this instance the housing 10 is not enclosed in an insulating casing as in my prior application, for I find that an insulating casing in addition to the cup-shaped metal 5 housing is unnecessary. The terminals of the coil 11 may be brought out through the housing in any suitable manner, and in Fig. 2 the housing is shown as provided with insulating bushings 18 through which the 10 terminals are designed to be extended.

One important feature of the present invention resides in the special shape of the cup or distribution of the metal of which the cup 10 is formed. In this instance the 15 metal is not of uniform thickness in the base and cylindrical wall of the housing as in my prior application. On the other hand, the cylindrical wall is reduced in thickness, and the base is of varying thickness, the thickness 20 being greatest adjacent the central hole 10^a, and the thickness gradually tapering off or being reduced until it meets or merges into the cylindrical wall.

Though I do not desire to be confined to 25 any particular proportions or thickness of metal at any given point, the thickness of the metal at one point relative to the thickness at any other is such that I obtain uniform flux carrying capacity in all parts of 30 the base of the cup and in the cylindrical wall of the cup. That is to say, the area of any circular section of the base from the central part to its periphery is substantially the same and substantially the same as the cross- 35 sectional area of the cylindrical wall of the housing. By decreasing the thickness of the base from the central part outward and making the thickness of the cylindrical wall the same as the thickness of the periphery of 40 the base, the metal of the housing irrespec- 45 tive of where the section is taken has the same flux carrying capacity this being of very great importance for the reason that in this case as in my prior application the one magnetic pole of the housing is at the open top and the opposite pole is at the center of the base.

Another condition that I prefer to bring 50 about in the present construction is a cer- 55 tain relation in the cross-section of the core and the cross-section of the housing at any point so long as the cross-section is taken at right angles to the course of the flux thread- 60 ing through it. That condition or relation is equality of the cross-sectional areas so that 65 the core and cup or housing will have the same flux carrying capacity.

As before stated, both the core and housing 70 are permanent magnets and both are 75 preferably formed of good magnet steel com- 80 monly employed in making permanent mag- 85 nets for high grade instruments, and after 90 the core and coil are formed of the proper 95 shape and size, the core can be set into the 100 center of the housing and clamped in place,

and both can be simultaneously magnetized with the receiver coil traversed by current such as to saturate both parts.

By having the area of cross-section of the core the same as the area of cross-section of the housing, whether the cross-section of the latter is taken through the cylindrical part or through the base with the section circular and cut on any radius, all parts of the core and housing will be magnetized to precisely the same amount. This condition not only avoids an unnecessary amount of metal in one part or the other, but enables both magnets to be used effectively, one in conjunction with the other in the production of fields which assist one another, but also the initial magnetism is more effectively maintained than would otherwise be the case.

In forming this housing it may be initially 85 of the same thickness throughout as shown by dotted lines in Fig. 4, in which event the cylindrical wall is turned or ground down to the desired final thickness, and the base is then tapered off by cutting or grinding so as 90 to leave the right distribution of metal to produce the results above stated. This is, of course, done before the steel is hardened preparatory to the magnetizing step.

It is because the steel of which the cup is 95 formed is hardened to an exceedingly high degree that the threads which receive the 100 threads of the cap 16 when the latter is screwed in place are formed in a separate ring. This ring is preferably formed of iron or machinery steel, low in carbon, so that 105 it can be readily machined after the housing itself has been hardened. Generally the ring 17 is brazed to the cup or housing 10, and this can be done by copperplating the 110 cup and also the ring, the copper applied during the plating serving as the brazing material to permanently fasten the ring to the cup. After the hardening process the threads then can be cut on the ring, it being 115 desired that they be cut subsequent to the hardening process so as to avoid distortion of the threads when the parts are heated.

A further important feature of the present invention resides in the special shape 115 of the diaphragm 15. It will be noted that the thickness of the diaphragm gradually decreases from the central part or part op- 120 posite the core toward the peripheral part which is clamped between the cup and the top or open end of the housing where a thickened rim portion 15^a is provided for clamping purposes. In forming this dia- 125 phragm the same condition is maintained as in forming the base of the cup, that is to say, the cross-sectional area of any cir- 130 cular section with the center of the dia- phragm as an axis is substantially the same as the cross-sectional area of every other sec- 135 tion, irrespective of where the section is taken, from that portion which is directly

opposite the core indicated by the dotted circle 15^b of Fig. 6 to the thickened rim portion 15^a.

In producing this diaphragm a flat disk is utilized of uniform thickness from the center to the periphery, and then one or both faces are ground or cut down, producing a diaphragm of gradually decreasing thickness from the central part outward. This diaphragm may be cut or ground down on one side only as shown in Fig. 1 and Fig. 5, in which event one side, generally the under side will be flat, or the cutting or grinding may be done on both surfaces as shown in Fig. 6 where the diaphragm is designated 15^x. In either event the tapered surface or surfaces may be extended to the center of the diaphragm, but the central part of the diaphragm opposite the core may be and preferably is of uniform thickness.

In thus forming the diaphragm, two very important advantages are obtained. In the first place, the flux carrying capacity of the diaphragm is the same on any circular section between the central part opposite the core and the periphery where it is clamped in place as already explained, and furthermore, a uniform flexing is obtained when the diaphragm is vibrated, the flexing being substantially uniformly distributed from the periphery where it is clamped in place to the region of the center. In other words, the flexibility is that of a relatively thin diaphragm of uniform thickness, but at the same time there is sufficient metal opposite the core to carry a relatively large amount of flux, and therefore sufficient metal to enable vibration of large amplitude for a given change in the value of the current passing through the receiver coil.

Though the diaphragm may be in the form of a permanent magnet and may therefore be formed of good magnet steel as is utilized in forming the core and housing, I prefer that it be formed of soft iron which has greater permeability than magnet steel, and therefore for a given cross-section has greater flux carrying capacity.

Thus it will be seen that the improvements of this construction over that shown in my prior application are mainly of two-fold nature consisting first of a coil housing preferably in the form of a permanent magnet and formed so as to have uniform flux carrying capacity in the cylindrical part and in the base, with the flux carrying capacity of the core and cup or housing substantially the same, and secondly, in the provision of a vibratory diaphragm which may be formed of magnet steel or soft iron, preferably the latter, which is of gradually decreasing thickness from the central portion opposite the core to the per-

ipheral clamping portion, and has substantially equal flux carrying capacity from the region of the center outwardly to the portion which is clamped between the housing and cap. By these improvements above mentioned, the sensitiveness of the receiver to very feeble currents in the receiver coil is increased.

The above novel features are capable of conjoint use and to an extent may be used advantageously independently of each other. For example, it may be desirable to form the core 12 of soft iron instead of magnet steel. Likewise my improved diaphragm 15 may be used advantageously with other forms of receivers, and is not necessarily confined to one of the general type herein illustrated. Other changes may be made, and I aim in my claims to cover all modifications which do not involve a departure from the spirit and scope of my invention as defined in the appended claims.

Having described my invention, I claim:

1. A telephone receiver comprising a coil, a cup-shaped housing enclosing the coil and adapted to convey flux through the base and upright portion thereof, the flux carrying capacity of the base being substantially the same from the region of the center to the periphery.

2. A telephone receiver comprising a coil, a housing receiving the coil and having base and upright portions, a diaphragm at the open end of the housing, the flux carrying capacity of the housing through different portions of the base and through the upright portions being substantially the same.

3. A telephone receiver comprising a coil, a metal housing containing the coil and a vibratory diaphragm opposite the coil, said housing having a base portion which decreases in thickness from the central part toward the periphery.

4. A telephone receiver comprising a coil having a core, a cup-shaped metal housing receiving the coil and a vibratory diaphragm opposite the coil and core, the base of the housing being thickest adjacent the center and decreasing in thickness toward the periphery, and the upright wall of the housing having substantially the thickness of the peripheral portion of the base.

5. A telephone receiver comprising a coil having a core, a metal housing receiving the same and a vibratory diaphragm at the end of the housing opposite the coil and core, the housing having a base portion at one end of the coil and a portion extending up about the side of the coil, the area of annular sections of the base portion at different distances from the center being substantially the same.

6. In a telephone receiver, a metal coil housing having a central core extending

- from the base, the core and housing having substantially the same flux carrying capacity.
7. In a telephone receiver, a cup-shaped metal coil housing having a core extending from the base, the core and the base and upright portion of the housing having substantially the same flux carrying capacity.
8. In a telephone receiver, a cup-shaped metal housing for the receiver coil, said housing being a permanent magnet with one pole adjacent the center of the base and the opposite pole at the open end of the housing, the base of the housing being of decreasing thickness from the central portion outward.
9. In a telephone receiver, a cup-shaped metal housing for the receiver coil, said housing being a permanent magnet with one pole adjacent the center of the base and the opposite pole at the open end of the housing, the flux carrying capacity of the housing from one pole to the other being substantially uniform.
10. A telephone receiver comprising a coil, a metal housing containing the coil and a vibratory diaphragm opposite the coil, said housing being in the form of a permanent magnet and having a base portion which decreases in thickness from the central portion toward the periphery.
11. A telephone receiver comprising a coil having a core, a cup-shaped housing in the form of a permanent magnet receiving the coil and a vibratory diaphragm opposite the coil and core, the base of the housing being thickest adjacent the center and decreasing in thickness toward the periphery, and the upright wall of the housing having substantially the thickness of the peripheral portion of the base.
12. A telephone receiver comprising a coil having a core, a metal housing in the form of a permanent magnet receiving the same and a vibratory diaphragm at the end of the housing opposite the coil and core, the housing having a base portion at one end of the coil and a portion extending up about the side of the coil, the area of annular sections of the base portion at different distances from the center being substantially the same as the cross-sectional area of the upstanding portion.
13. In a telephone receiver, a metal housing having a base with an upstanding core and having an outer wall, a coil within the housing and a diaphragm at the open end of the housing, the housing and core being formed of permanent magnet steel, and said core base and outer wall having substantially uniform flux carrying capacity.
14. A vibratory diaphragm for a telephone receiver having substantially the same flux carrying capacity adjacent its periphery as in the region of the center.
15. A vibratory diaphragm for a telephone receiver formed so that annular sections cut on different radii are of substantially the same cross sectional area.
16. A telephone receiver comprising a cup-like housing containing a coil and a core, and a flexible metal diaphragm closing the end of the cup, the diaphragm having substantially the same magnetic flux carrying capacity from the central part opposite the core to the peripheral part adjacent the edge of the housing.

In testimony whereof, I hereunto affix my signature.

JOSEPH A. WILLIAMS.
